A. HEINTZ.
AUTOMOBILE FAN.
FILED JULY 1, 1921.

Inventor
Andrew Heintz,

Geo. H. Kimmel. *Attorney*

UNITED STATES PATENT OFFICE.

ANDREW HEINTZ, OF NEOSHO, WISCONSIN.

AUTOMOBILE FAN.

Application filed July 1, 1921. Serial No. 431,882.

To all whom it may concern:

Be it known that I, ANDREW HEINTZ, a citizen of the United States, residing at Neosho, in the county of Dodge and State 5 of Wisconsin, have invented certain new and useful Improvements in Automobile Fans, of which the following is a specification.

This invention relates to cooling fans for 10 automobiles and more particularly to a novel and improved design of fan whereby the maximum amount of air may be obtained to positively cool the radiator and engine.

15 The primary object of the invention resides in the provision of a novel and improved automobile fan having a plurality of equally spaced blades preferably seven in number, and one designed for use in connection with Ford automobiles as a substitute 20 for the standard fans now being manufactured.

A still further and very important object 25 of the invention resides in the construction of an automobile fan wherein the radially disposed blades are constructed and arranged in a manner whereby the maximum amount of air will be drawn into the body of the machine and prevent the engine from 30 being overheated, the parts of the fan structure being very simple in construction, easily assembled, rigid and durable, highly efficient in operation, practical yet capable of 35 being manufactured at a very low cost whereby its commercial possibilities are greatly enhanced.

With these and other objects in view, the invention consists in the construction of the novel combination and arrangements of 40 parts hereinafter fully described, illustrated with the accompanying drawings and pointed out in the subject matter being claimed, it being understood that various changes in the forms, proportion, size and minor details of construction within the scope of the 45 claims may be resorted to without departing from the spirit of the invention or sacrificing any of the advantages thereof.

In the accompanying drawing:

50 Fig. 1 is a front or face view of the fan,

Fig. 2 is a side view partly in section taken on a line 2—2 of Fig. 1,

Fig. 3 is a further view taken on line 3—3 of Fig. 1.

55 Referring now to the drawings wherein like characters designate corresponding

parts throughout the several views, 5 designates the hub and 6 the flanged pulley for receiving the usual driven belt (not shown) for rotating the fan as is well understood. 60 The hub and pulley are preferably formed integral with an annular, blade attaching plate 8 positioned centrally of a fan, said plate having connected thereto the fan including a central disk-like portion A integrally formed with a plurality of radially 65 extending blades 9, preferably seven in number whereby the maximum amount of air may be drawn into the body of the machine to cool the radiator and engine. The 70 respective blades 9 taper outwardly from their center where they are connected by suitable screw bolts or other fastening elements 10, the sides 11, 12 of said blades being curved so as to extend beyond the inner 75 and outer planes of and below the plate 8 which are connected to the disk-like portion of the fan in the manner clearly shown by Figure 1 of the drawings. Concentrically of the central disk-like portion A, is an annular rolled rim 13, connected with the respective blades by a narrow web B. It will be observed that the tips or outer ends of the blades 9 are spaced from the bead-like rim 13 and are integrally joined therewith, 80 through the medium of the web B. It will be obvious that the fan proper can be cut and stamped from a single piece of material. 85

A reinforcing spider 14 having a plurality of the arms 15 attached thereto are riveted 90 or otherwise secured as at 16 to each of the blades, the said fastening elements 10 extending through the plate 8, blades and spider thus providing a firm and rigid structure and preventing the possible fracturing of any one of the blades of the fan. 95

The fastening elements 10 extending through the parts above mentioned permit of the attachment of my improved blade structure to the hub and pulley of the 100 present type of fan now being used on Ford cars, which in practice has been found somewhat inefficient when the engine has been running for a long duration of time since sufficient air cannot be drawn into the body 105 of the machine by the four blades as at present used.

In the accompanying drawings, I have illustrated my invention embodied in one form by way of example, and which in 110 practice has been found to be highly satisfactory in obtaining the desired results. It

will be obvious however that other embodiments may be adopted and that various changes in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

Having shown and described my invention, what I now claim as new and desire to secure by Letters Patent of the U. S. is:—

1. An automobile fan wheel, comprising a single sheet metal blank cut and bent to provide a circular series of blades integrally joined together by a disk at the hub portion of the wheel and integrally joined about the periphery by a circular rolled rim, the blades, with the whole fan structure being in one piece and each blade having a radially

twist increasing in degree from the hub to the rim portion and dished symmetrically with respect to the front face of the blade. 25

2. An automobile fan wheel, comprising a single sheet metal blank cut and bent to provide a circular series of blades integrally joined together by a disk at the hub portion of the wheel and integrally joined about the periphery by a circular rolled rim, the blades, with the whole fan structure being in one piece and each blade having a radially twist increasing in degree from the hub to the rim portion and dished symmetrically 35 with respect to the front face of the blade, one of the edges of all the blades being located in substantially one plane and the other edges of all the blades distant from the first named edge being of progressively 40 increasing distance from said plane.

In testimony whereof, I affix my signature hereto.

ANDREW HEINTZ.
